DESIGN FOR A PERPETUAL CALENDAR

Albert George McNeill and Lawrence Niles Olsen,
Philadelphia, Pa., assignors to Bachmann
Brothers, Inc., Philadelphia, Pa., a corporation
of Pennsylvania

Application March 23, 1945, Serial No. 118,649

Term of patent 14 years

(Cl. D74—5)

To all whom it may concern:

Be it known that we, Albert George McNeill and Lawrence Niles Olsen, citizens of the United States, residing at Philadelphia, in the county of Philadelphia and Commonwealth of Pennsylvania, have invented a new, original, and ornamental Design for a Perpetual Calendar, of which the following is a specification; reference being had to the accompanying drawing forming a part thereof, in which

Figure 1 is a front elevational view of a per-

petual calendar, showing our new design, the numerals and printed matter being merely representative of what would appear in these openings from time to time.

Figure 2 is a side view of the calendar shown in Figure 1.

We claim:

The ornamental design for a perpetual calendar, as shown and described.

ALBERT GEORGE MCNEILL.
LAWRENCE NILES OLSEN.
